(57) **CLAIM**

I claim the ornamental design for a game board, as shown and described.

DESCRIPTION

FIG. 1 is a top perspective view of a game board showing my new design;

FIG. 2 is a bottom perspective view thereof;

FIG. 3 is a top plan view thereof;

FIG. 4 is a left side elevational view thereof; the right side elevational view being a mirror image thereof;

FIG. 5 is a bottom plan view thereof; and,

FIG. 6 is a front elevational view thereof; the rear elevational view being a mirror image thereof.

1 Claim, 4 Drawing Sheets

FIG. 2

FIG. 3

FIG. 4
